LOAD EJECTOR

George S. Allin, Seattle, Wash.; assignor to
Isaacson Iron Works, Seattle, Wash., a corpora-
tion of Washington

Application September 18, 1939, Serial No. 295,462

(13 Claims. (CL. 37—126)

This invention relates to dirt moving and transporting vehicles, and it has reference more particularly to improvements in power actuated load ejection mechanism for dirt hauling vehicles, particularly for load hauling scrapers of the character described in my prior Patent 2,214,240.

While the present invention, as hereinafter described, is illustrated in connection with the vehicle disclosed in the above numbered application, it is to be understood that it is not confined thereto, but may be utilized with dirt handling vehicles of various kinds where the associated parts are similarly arranged.

It is the principal object of this invention to provide a simple and effective power actuated means whereby the carried material, or load, may be positively and fully ejected from the scraper when, by reason of its character, it will not discharge freely by gravity flow.

Explanatory to this invention, it will be here mentioned that the machine of the application above identified comprises a bowl, open at the front and bottom, and equipped with a rearwardly and upwardly inclined back wall having a blade at its lower edge which effects the digging or scraping up of the dirt when the bowl is lowered to a position that will bring the blade into ground contact. Also, there is a gate mounted in the bowl, forwardly of the blade and back wall, and adapted to be closed under the run of material that may be pushed ahead of the blade, to pick it up and retain it in the bowl for transportation. When the gate is opened, the transported load will be automatically discharged by gravity flow by reason of the degree of inclination of the back wall and position of the gate. However, in the event that the dirt is wet, or muddy, the discharge is retarded, and in some cases, its ejection by positive ejection means becomes necessary.

In view of the above, it has been the principal object of this invention to provide mechanically powered means that may be associated with the back wall of the scraper described, or with similar scrapers, for the positive ejection of material whenever positive ejection is necessary.

It is a further object of the invention to provide mechanically powered ejection means, for a scraper of the kind above described which operates under control of movement of the gate in that it is adapted to be set in motion for ejection of a load incident to actuation of the gate to a predetermined open position, and to be auto-

matically returned to normal position with the closing of the gate.

Still another object of this invention resides in the provision of hydraulic, or fluid pressure controlled mechanisms for actuating the gate and ejector, and to so connect together the piping systems of these mechanisms that movements of the ejector and gate are placed under control of a valve that is common to both.

Other objects of the invention reside in the details of construction of parts, in their combination and mode of operation, as will hereinafter be described.

In accomplishing these and other objects of the invention, I have provided the improved details of construction, the preferred forms of which are illustrated in the accompanying drawings, wherein—

Fig. 1 is a side view of a load hauling scraper embodying the present invention, showing the scraper bowl raised to load transporting position, and the gate closed to retain the load.

Fig. 2 is a plan view of the machine.

Fig. 3 is a view of the machine in longitudinal section, with the blade in digging contact with the ground and the gate partially opened.

Fig. 4 is a sectional view of the machine illustrating the functional action of the ejector mechanism.

Fig. 5 is a diagrammatic illustration of the hydraulic system for opening the gate and operating the ejector mechanism.

Fig. 6 is a sectional detail of the hydraulic cylinder at one side of the bowl for actuation of the gate.

Fig. 7 is an enlarged detail of the automatic valve associated with the hydraulic cylinder of the gate actuating system.

Fig. 8 is a diagrammatic illustration of the control valve for the hydraulic system.

Referring more in detail to the drawings—

The scraper frame, which for convenience, will be referred to as the "bowl," is designated in its entirety by reference numeral 1. This bowl comprises opposite side walls 2 and 2' of substantial height and length, connected substantially and rigidly together across the forward end of the bowl by a horizontal member 3 which, in this instance, is in the form of a tubular beam and is disposed across the top edge of the bowl.

The forward end of the bowl; that is, the space between the forward ends of opposite side walls, is open, as is also the bottom of the bowl, except for the gate, presently to be described. The rear end of the bowl; that is, the space between the

rearward edges of the side walls, is permanently closed by a forwardly and downwardly inclined wall 4, designated as the "back wall"; this wall being equipped at its lower edge with a scraping blade 5, having its lower, cutting edge extended somewhat below the lower edges of the side walls to adapt the blade for the intended scraping and digging operation. The back wall is substantially reinforced by suitable cross beams, designated at 4a, and its top edge is approximately 10 midway of the top and bottom edges of the side walls.

The bowl is supported at its forward end, for transportation, through the mediacy of a goose-neck bracket 6 that is rigidly fixed centrally to the cross beam 3 and extends forwardly and downwardly therefrom and at its forward end is pivotally fixed to a knuckle 7, which, in turn, is pivotally mounted on a cross axle 8 in such manner as to permit universal movement of the 15 axle. The axle is equipped at its ends with ground wheels 9, and a draw bar, or tongue, 10, is attached to the axle as a means for towing the device from a tractor, or the like.

At its rearward end, the bowl is supported for 25 transportation and vertical adjustment by a pair of laterally spaced ground wheels 11, each of which is mounted by a vertically adjustable frame 12. These two frames are pivotally hinged, as at 13, to the rear end wall at opposite sides of the bowl and, at their rearward ends, have horizontal spindles 14 fixed therein on which the ground wheels 11-11 are mounted. The vertical adjustment of the frames 12 is to provide for 30 vertical adjustment of the bowl, and the movement of each frame is under control of a telescopic, hydraulic jack or cylinder 15, comprising a series of cylinder sections telescopically associated together, forming a closed container for a hydraulic pressure medium. The larger section in each set is at the upper end of the jack, as shown herein, and is pivotally attached to the rear wall of the bowl as at 16, while the lower section is pivotally attached, as at 17, to the corresponding frame 12. Thus, by applying a 35 hydraulic pressure medium into the cylinders, they will be extended thereby to cause the frames to swing downwardly relative to the bowl with a resultant lifting of the bowl relative to the ground. By relieving the cylinders of the hydraulic medium, the weight of the supported bowl will cause the frames to swing upwardly relative to the bowl and the bowl will be lowered toward the ground accordingly. The control of application of the hydraulic medium to the cylinders 15 thus provides for control of the position of the 40 bowl relative to the ground.

As will be observed best by reference to Fig. 3, the rear wall 4 of the bowl is so inclined that, with the blade in digging contact with the ground, there will be a relatively easy scraping action and a comparatively easy pushing of earth across the blade and up the back wall into the bowl, to be retained between the opposite side walls.

It will be understood that it is not necessary for the gate to be fully opened during the loading operation, but only open sufficient to clear the ground when the blade is in digging position. Dirt that is scraped up is advanced up the back wall as the vehicle moves forwardly, and finally falls forwardly and is either retained by the gate or is merely pushed ahead of the blade. However, for a leveling off operation wherein the back wall is used merely as a scraper blade, the gate is usually lifted to a substantial height so

as not to obstruct easy disposal or distribution of dirt that is pushed ahead of the blade when it passes over a depression. In other words, it is only necessary that the gate be so adjusted that it will not interfere with the back wall of the bowl being used in the capacity of an ordinary scraper for leveling operations.

The gate, designated in its entirety by reference numeral 20, extends transversely between the opposite side walls of the bowl, to serve as a closure for the front end and for the bottom of the bowl when it is desired to transport a load, as will be seen in dotted outline in Fig. 1. In this instance, the gate is of substantial height, and is supported from its opposite side edges by brackets, or plates 21, fixed rigidly thereto and lying close to the side walls inside of the bowl. These plates 21 are rigidly jointed by short horizontal cross beams 22 to the forward ends of bell crank levers 23 that are pivotally mounted on the corresponding side walls of the bowl by pivot studs 24.

It will be observed that the gate is adapted to swing about the axial line of the studs 24 and that the side walls of the bowl are arcuately slotted, as at 25, for travel of the ends of the short beams 22 in the raising and lowering operation. When the gate is closed, these slots are covered by the upper portions of the plates 21, which are so formed, as at 21a, as to also cover the slots 25 when the gate is open.

As will be noted in Fig. 1, each of the bell crank levers has an arm 23a extending forwardly from the supporting pivot 24, and fixed at its forward end to the cross beam 22, and has another arm 23b extending downwardly and rearwardly and pivotally connected at its end, as at 26, to the end of the piston rod 27a that extends from a piston 27b that is reciprocally contained in a hydraulic cylinder 27. The hydraulic cylinder is located below and forwardly of the bell crank lever, and is supported from the bowl by a pivot 28, carried by a supporting bracket 29 on the outside of the side wall.

The arrangement of the hydraulic cylinders 27 and their connections with the bell cranks 23 is such that when the piston rods are extended, the gate will be held in closed position, and when they are retracted, the gate will be moved accordingly toward an open position. Actuation of the pistons of the hydraulic cylinders is under control of a hydraulic pressure medium that is applied to the forward ends and relieved from the rearward ends of the cylinders or vice versa through pipes 56 and 57, respectively, as presently will be described in connection with the control system for the gate and ejector mechanism, and illustrated in Fig. 5.

Now describing the present ejector mechanism which is best shown in Figs. 2, 3 and 4:

It will be observed, as previously noted, that the top edge of the back wall 4 of the bowl terminates about midway of the blade and top of the bowl. Continuing from this back wall, is the ejector comprising a wall section 35, which, in normal position, slightly overlaps the front face of the top edge of the back wall, and curves forwardly and upwardly as a continuation of the back wall 4 to even with the top edges of the side walls of the bowl. This wall section 35 is supported at its opposite ends by a pair of lever arms 37-37 which are fixed, respectively, to the opposite end portions of a cross shaft 38 that is horizontally disposed back of the wall 35 and 70 revolubly contained in the rear edge portions of

the side walls of the bowl, as at 38a. At their upper ends, the lever arms 37-37 are pivotally fixed to brackets 39 on the back side of the wall section 35. Fixed on the opposite ends of the cross shaft 38, adjacent the outside of the side walls of the bowl, are lever arms 40, each pivotally attached at its end, as at 41, to a piston rod 42 extending from a piston 43 contained in a hydraulic cylinder 44; the cylinder being pivotally fixed, as at 45, to a bracket 46 attached to the side wall of the bowl. Pressure medium from a source of supply may be selectively applied to the forward ends or to the rearward ends of these cylinders to extend or retract the piston rods, thus to rotate the cross shaft 38, and, through the action of lever arms 37-37, to move the ejector wall sections 35 from the position shown in Fig. 3 to the position shown in Fig. 4. When this ejector wall section is actuated downwardly, it operates as a scoop, sliding down the back wall 35, to forcibly eject material from the bowl.

In Fig. 5, I have illustrated the hydraulic system for control and actuation of the gate and ejector.

In this view, 50 designates a tank, for a supply 25 of hydraulic pressure medium, connected by a pipe 51 with a pressure pump 52 from which a delivery pipe connection 53 leads to one side of a four-way control valve 54. Valve 54 also has a return pipe connection 55 leading to tank 50. 30

Leading from control valve 54 is a delivery pipe 56 connecting to the forward end of cylinder 27. Also, a pipe 57 leads from valve 54 and this has connection with the rearward ends of both cylinders 27 and 44. A pipe 59 connects 35 the forward end of cylinder 44 with the forward end of one of the cylinders 27 through an automatic back check valve 60 mounted by the cylinder 27 to prevent flow from cylinder 44 to cylinder 27 through this connection. The valve 60 has an operating stem 62 adapted to be engaged by the piston 27b of cylinder 27 to open the valve only when the piston has moved to a position for 40 fully opening the gate. A coiled spring 65 acting against the valve urges it toward its closed position when held open by the piston acting against the stem.

While it is not herein illustrated, it is the intention that the pump, tank and main control valve of this system be located on the tractor or device pulling the scraper and that the piping 56 and 57 used between the tractor and scraper should be flexible. It is also contemplated that corresponding cylinders at opposite sides of the machine be connected together and that the pipes 56 and 57 be attached to these connection pipes, thus to effect an equal and simultaneous application of pressure medium to the cylinders at opposite sides of the vehicle.

It is also anticipated, as shown in Fig. 5, that the hydraulic jacks 15 be connected together and that the pipes 10 which lead from a two-way valve 11 to these cylinders, be connected to the pressure line 53 by a line 72 and have a return pipe 73 from the valves to the tank 50, so that an equal application of pressure will be made to the jacks.

With the parts so constructed, assuming the bowl is loaded and raised for transportation, and it is desired to open the gate for discharge of a load from the bowl that does not require positive ejection, the valve 54 is adjusted to a position to direct flow of pressure medium from the pump through pipe 57 to the rear ends of both cylinders 27 and 44. However, since valve 60 in

this case will remain closed and the hydraulic medium cannot be relieved from the cylinder 44, the piston 43 cannot be moved and as a result, the ejector remains inactive while the pressure applied to cylinder 27 causes the piston 26 to move forwardly, thus to actuate the bell cranks to move the gate toward open position, to discharge the load. In the case of freely discharging material, the gate is not opened to its limit and therefore the ejector device will not be actuated from the position of Fig. 1.

Assuming that a positive ejection of material is necessary, the pressure medium is applied to fully open the gate, and incidentally moving the piston 27b to contact valve stem 62 to open valve 60 for a release of medium from the forward ends of the cylinders 44 into cylinders 27, thus permitting the pressure acting on the pistons 43 to rotate the shaft 38 to move the ejector wall 35 downwardly to the position as shown in Fig. 4 for a positive ejection of the load.

It will be understood that when the piston 27b comes forwardly and engages the valve opening stem 62, the liquid from cylinder 44 flows into cylinder 27 and across the recessed face of piston 27b to the outlet pipe 56, leading back to valve 54 and thence to tank 50.

When the control valve 54 is adjusted to a position to effect an application of pressure for returning the ejector to normal position, pressure is first delivered through pipe 56 to cylinder 27, and through valve 60 and pipe 59, to cylinder 44. In the structure shown in Figs. 5 and 6, the pressure operates first to move the piston 27b to close the gate, then it acts on piston 43 to return the ejector to normal position. When the ejector is once returned to its normal position, it will be held there, due to valve 60, until the valve is positively opened by the piston 27b acting on the valve stem 62.

Having thus described my invention, what I claim as new therein and desire to secure by Letters Patent is:

1. In a vehicle of the character described, a load receiving bowl having opposite side walls and a rearwardly inclined back wall equipped along its lower edge with a scraping blade for filling the bowl, a load ejecting shoe extending between the side walls as a continuation of the back wall, and a supporting means for the shoe operable to actuate it, with an initial forward tilting action, downwardly along the back wall for a forcible ejection of a load from the bowl.

2. In a vehicle of the character described, a load receiving bowl having opposite side walls, and an upwardly and rearwardly inclined, load sustaining back wall, a blade fixed to the lower edge of the back wall for filling the bowl, a pivotally supported load ejection shoe normally disposed with its bottom edge resting upon the back wall near the top edge thereof and extending between the opposite side walls as a continuation of the back wall; said ejection shoe comprising a wall plate that, in normal position of the shoe, continues from the top edge of the back wall in an upwardly and forwardly curved direction to effect a forward deflection of material moving upwardly against it, and means pivotally supporting the shoe and operable for the actuation of said shoe forwardly at its top edge, then to move it downwardly with its bottom edge in sliding contact with the back wall as a scoop for a forcible ejection of material from the bowl.

3. A vehicle of the character described, comprising a bowl having opposite side walls, and

rearwardly inclined back wall; a load ejection shoe normally disposed across the top edge of said back wall as a continuation thereof and with its lower edge in supporting contact with the back wall; a cross shaft mounted by the bowl back of the lower edge of said shoe, upwardly extending lever arms fixed to the cross shaft, and pivotally attached at their ends to the shoe for support and actuation thereof, and means for rotatably actuating the shaft to effect an initial forward tilting action of the shoe, and then travel thereof downwardly in sliding contact with said back wall for ejection of a load from the bowl.

4. A structure as recited in claim 3 wherein the means for rotatably actuating said cross shaft comprises a lever arm on the shaft and a double acting hydraulic jack mounted on a side wall of the bowl including a piston and rod and means connecting the piston rod with the said lever arm for effecting the rotation of the shaft in opposite directions for the functional actuation of the shoe and for its return to normal position.

5. In a vehicle of the character described, a bowl having opposite side walls, a rearwardly and upwardly sloping back wall, having its top edge terminating substantially below the top edges of the side walls, a cross beam extending between the top edges of the side walls at the back end of the bowl and a load ejection shoe including a wall plate which, in normal position of the shoe, is disposed as a continuation of the back wall and overlapped therewith at its lower edge and having its top edge portion curved upwardly and forwardly and normally sustained against rearward tilting by resting against the said cross beam, and means mounted on the bowl and pivotally attached to the shoe for supporting and actuating the shoe slidably downward along the back wall for the ejection of a load from the bowl.

6. In a load hauling vehicle of the character described, a bowl, a gate for the bowl movable between closed and open positions, a load ejection shoe movable between normal and load ejecting position, means operable by hydraulic pressure medium for moving the gate, means operable by hydraulic pressure means for actuating the shoe, a source of pressure medium, a piping system connecting the source of supply with the hydraulic means for the gate and shoe, a control device for simultaneously applying actuating pressure to each of said means, a control valve in the shoe actuating system operable under control of the gate operating devices for restraining the shoe against movement until the gate is in a predetermined open position.

7. In a load hauling vehicle of the character described, a bowl, a load ejection shoe associated with the bowl, a gate for the bowl movable between closed and "full open" positions, a hydraulic jack mounted on the bowl and having a piston operatively connected for actuating the gate, a hydraulic jack on the bowl having its piston operatively connected for actuation of the shoe, a source of supply of hydraulic pressure medium, a piping system connecting said source of pressure medium with the hydraulic jacks, a control device for applying the hydraulic pressure medium to the jacks for opening the gate, and for functionally actuating the shoe, and a normally closed check valve in the hydraulic system for the shoe, restraining the piston in the shoe actuating jack against movement, said valve being disposed in position to be opened by the piston

of the jack which actuates the gate when the gate reaches its "full open" position.

8. In a load hauling vehicle of the character described, a bowl, a load ejecting shoe associated with the bowl, and movable between retracted and load ejecting positions, a gate for the bowl movable between open and closed positions, a hydraulic jack mounted on the bowl and having its piston operatively connected for actuation of the gate to its different positions by its movement to opposite limits of travel, another hydraulic jack mounted on the bowl having its piston operatively connected to actuate the shoe to its different positions by its movement to opposite limits of travel, a source of hydraulic pressure medium for actuation of the jacks, two pipes associated with the source of pressure medium selectively usable as pressure applying and return pipes; the first pipe having connection with both jacks for the simultaneous application of pressure medium to open the gate and functionally actuate the shoe, the second pipe having connection with each jack for application of pressure to close the gate and return the shoe to its retracted position, a valve device associated with the pipes for controlling the application of medium to said jacks, and a back-check valve in the second of said pipes normally retaining the pressure medium at one side of the piston in the shoe actuating jack against outflow, thereby to hold the jack against actuation of the shoe during travel of the gate to open position, and means arranged to be actuated by the piston of the jack which actuates the gate, incident to the gate reaching a predetermined open position, to open said back-check valve to relieve said hydraulic medium from the shoe actuating jack and permit the action of the jack whereby the shoe will be functionally actuated.

40 9. A device as in claim 8 wherein the second pipe connection between the source of pressure medium and the hydraulic jacks is through the cylinder of the gate actuating jack, and said back-check valve has an actuating stem arranged to be engaged by the jack piston to open the valve.

10. In a vehicle of the character described, comprising a bowl, a load retaining gate, a load ejector in the bowl, a double acting hydraulic jack for actuating the gate between open and closed positions, a double acting hydraulic jack for actuating the ejector from retracted to extended position, a source of hydraulic pressure medium, a piping system for the application of the pressure medium to the jacks, a control valve operable for simultaneously applying the medium to the jacks and a valve in the system operable to retain the pressure medium against escape from one side of the second mentioned jacks to retain the ejector against functional movement and adapted to be opened by the final action of the first mentioned jack in moving the gate to open position.

11. In a vehicle of the character described, a load receiving bowl having opposite side walls and a back wall of lesser height than the side walls, and sloping downwardly and forwardly, and having a scraping blade across its lower edge, a load ejector comprising a plate normally disposed as an uninterrupted upward continuation of the back wall and means for actuating the ejector plate downwardly along the back wall.

12. In a vehicle of the character described, a load receiving bowl having opposite side walls and a back wall of substantially lesser than the

height of the sidewalls and having a scraping blade across its lower edge extending slightly below the lower edges of the side walls, and a load ejector comprising a plate normally disposed as an uninterrupted upward continuation of the back wall extending to the heights of the side walls and forwardly curved across its top edge, and means for actuating the ejector downwardly along the back wall.

13. In a vehicle of the character described, a 10 load receiving bowl having opposite side walls and a back wall of approximately one-half the

height of the sidewalls and having a scraping blade across its lower edge extending slightly below the lower edges of the side walls, and a load ejector comprising a plate normally disposed as an uninterrupted upward continuation of the back wall extending to the heights of the side walls and forwardly curved across its top edge, and means for actuating the ejector downwardly along the back wall with a co-incident forward action of the top portion to a position slightly advanced beyond the lower edge portion.

GEORGE S. ALLIN.
